PORTABLE RADIO RECEIVER WITH DETACHABLE SPEAKER WINGS

Dominick F. Sementa, Basking Ridge, N.J., assignor to
International Telephone and Telegraph Corporation,
Nutley, N.J., a corporation of Maryland

Filed Apr. 1, 1965, Ser. No. 84,560

Term of patent 14 years

(Cl. D56—4)

Fig. 1

Fig. 2

Fig.3

Fig.4

FIGURE 1 is a perspective view of the top, front and right side of a portable radio receiver with detachable speaker wings in assembled position showing my new design;

FIGURE 2 is a right side elevational view, to an enlarged scale, the opposite side being substantially a mirror image thereof;

FIGURE 3 is a perspective view of the top, front and right side of the portable radio receiver of FIGURE 1 with the handles parted from each other and pivoted down, and with one speaker wing partially detached; and

FIGURE 4 is a perspective view of the front and top of the portable radio receiver of FIGURE 1 with the speaker wings fully detached.

The dominant features of my new design are shown in solid lines in the drawings.

I claim:

The ornamental design for a portable radio receiver with detachable speaker wings, substantially as shown and described.
